Attorney

UNITED STATES PATENT OFFICE

JAMES A. O'BRIEN, OF ROSEMONT, PENNSYLVANIA, ASSIGNOR TO THE DE LONG HOOK AND EYE COMPANY, OF PHILADELPHIA, PENNSYLVANIA, A CORPORATION OF PENNSYLVANIA

HAIRPIN PACKAGE

Application filed April 1, 1932. Serial No. 602,433.

This invention relates to a method of packaging hairpins and the package produced thereby, and is particularly applicable to hairpins made from a section of flattened 5 wire stock bent approximately midway of its length to provide two substantially parallel leg portions connected by a loop.

In packages of this general character heretofore known and used the hairpins have 10 been more or less loosely mounted so that they are easily disarranged before the packages reach the purchaser in the usual trade channels. It is therefore an object of the invention to so support the pins within the 15 package that they are held in a predetermined position and may not be easily disarranged. It is a further object of the invention to provide a package in which the pins are supported upon one edge of the material 20 of which the package is formed and in such a manner that a portion of the package material is folded about the loops of the pins to retain them in position. It is a still further object of the invention to provide a 25 simple and inexpensive method for packaging hairpins whereby they may be fully protected within the package and not easily disarranged therein.

In order that the invention may be fully 30 understood, reference may be made to the accompanying drawing wherein:

Fig. 1 is a perspective view of the sheet of material from which the package is made;

Fig. 2 is a perspective view of the sheet 35 with the pin supporting portion partly folded and the pins in place thereon;

Fig. 3 is a longitudinal sectional view taken through the partially formed package as shown in Fig. 2;

Fig. 4 is a perspective view showing the pin 40 supporting portion of the sheet, with the pins thereon, in completely folded condition.

Fig. 5 is a perspective view of the completed package; and

Fig. 6 is a sectional view taken transversely 45 of the completed package shown in Fig. 5.

In forming the package constituting my invention, I utilize a sheet 10 of foldable material which is sufficiently rigid to give the 50 requisite protection to such a package as it

is handled in ordinary channels of commerce. This sheet may be made from cardboard of light weight, and is preferably of elongated shape with a length approximating three times the length of the pins to 55 be packaged therein. In forming this sheet of material it is preferable to crease the same along two transverse lines 11-12 and 13-14 in order that the sheet may be readily folded on these lines to form three substantially 60 rectangular portions, the pin supporting portion 15, the intermediate portion 16, and the flap portion 17. A slit 18 is provided in the pin supporting portion 15 and this slit extends transversely of the sheet in a direction generally parallel to the lines of fold 65 and terminates short of the lateral edges of the sheet as shown in the various figures of the drawing.

In the formation of the package a plurality 70 of pins 19 are mounted upon the pin supporting portion 15 so that the legs 20 and 21 of the pins are on opposite sides of the supporting portion with the loops 22 thereof in engagement with the free edge 23 of this portion. The ends 24 of the legs 20 on one side 75 of the supporting portion are extended through the slit 18, and, as will be noted, the pins are arranged in such adjoining relation alongside each other on the supporting portion of the package that they are not readily 80 displaceable, particularly after the package is completed.

While it is preferable to position the pins upon the supporting portion 15 before this 85 portion is folded along the line 11-12 into the position shown in Fig. 4 of the drawing, it will be understood that the sequence of these operations is not material to the invention, and that the pins may be positioned on 90 the supporting portion 15 after this portion has been folded substantially into the position shown in Fig. 4.

After the pins have been mounted upon the supporting portion 15 as described, and this 95 portion, with the pins thereon, has been folded into overlying relation with respect to the intermediate portion 16 as shown in Fig. 4, the flap portion 17 is then folded about the edge 23 of the supporting portion and the 100

edge 25 of this flap is inserted in the slit 18 as shown in Fig. 5. In thus folding the flap portion 17 about the free edge of the supporting portion 15, the inner faces of the flap portion 17 and the intermediate portion 16 contact closely with the pins adjacent the loops thereof as shown at 26 and 27 and thus serve to retain the pins in their proper position upon the supporting portion of the sheet 10 in the completed package. In order that the flap portion 17 may be readily inserted within the slit 18, the corners may be removed as indicated at 28 and 29 to form a tab 30, or the entire side edges of the flap portion may 15 be tapered for the same purpose.

By means of the structure herein described I provide a package in which the pins are supported in such a manner that they are not easily displaced from their proper position 20 in the package, and by the use of a single sheet of material a package is made in which portions of the package wrapper serve to retain the pins in their proper position. While the package has been designed particularly 25 for use with hairpins, it will be understood that it is likewise adapted for use in packaging other similar articles.

Having thus described my invention, what I desire to secure by Letters Patent is:

30 1. In a hairpin package, an elongated sheet of rigid material folded on two lines extending transversely thereof to provide three overlying rectangular portions of substantially equal length, one of the end portions 35 having a slit extending transversely thereof adjacent a line of fold, a plurality of hairpins mounted astride the edge of said end portion with the ends of the legs on one side of said portion extending through said slit and the 40 loops in engagement with said edge, the free edge of the opposite end portion being inserted within said slit.

2. In a hairpin package, a sheet of rigid material having one end thereof reversely 45 folded upon itself to provide a supporting portion with a length substantially equal to the length of the hairpins, said supporting portion having a slit extending transversely thereof adjacent the line of fold, a plurality 50 of hairpins mounted astride said end portion with the loops thereof in engagement with the edge of said portion and the ends of the legs on the outer face of said portion extending through said slit, the opposite end of said 55 sheet being reversely folded about the edge of the supporting portion into engagement with the pins and having its free edge inserted within said slit.

3. A hairpin package comprising an elongated sheet of rigid material folded upon itself to provide a pin supporting portion, said pin supporting portion having a transverse slit therein terminating short of the lateral edges, a plurality of pins mounted astride the 65 pin supporting portion with the loops in en-

gagement with the free edge thereof and the ends of the legs on the outer face of the pin supporting portion extending through said slit, the opposite end of said sheet being folded about the loops of the pins and having a tab thereon inserted in said slit.

In testimony whereof, I have signed my name to this specification.

JAMES A. O'BRIEN.
